(57) **CLAIM**

The ornamental design for a cosmetic container as shown and described.

DESCRIPTION

FIG. 1 is a front perspective view of a cosmetic container showing the new design.

FIG. 2 is a front elevation view of the cosmetic container.

FIG. 3 is a rear elevation view of the cosmetic container.

FIG. 4 is a right side view of the cosmetic container.

FIG. 5 is a left side view of the cosmetic container.

FIG. 6 is a top view of the cosmetic container.

FIG. 7 is a bottom view of the cosmetic container.

FIG. 8 is an exploded perspective view of a first embodiment of the cosmetic container having portions shown with dashed lines; and,

FIG. 9 is an exploded perspective view of a second embodiment of the cosmetic container having portions shown with dashed lines.

The appearance of any portion of the cosmetic container shown with dashed lines forms no part of the claimed design.

1 Claim, 9 Drawing Sheets
